Primary Examiner—Kay H. Chin*Attorney, Agent, or Firm*—Knobbe, Martens, Olson & Bear[57] **CLAIM**

The ornamental design for a snowboard binding, as shown and described.

DESCRIPTION

FIG. 1 is a top perspective view of the snowboard binding showing my new design;
 FIG. 2 is a top plan view thereof;
 FIG. 3 is a bottom plan view thereof;
 FIG. 4 is a front elevational view thereof;
 FIG. 5 is a rear elevational view thereof;
 FIG. 6 is a right side elevational view thereof;
 FIG. 7 is a left side elevational view thereof;
 FIG. 8 is a top plan view of the base member of the snowboard binding, the remaining portion of the snowboard binding being omitted for convenience of illustration and clarity;
 FIG. 9 is a bottom plan view of FIG. 8;
 FIG. 10 is a front elevational view of FIG. 8;
 FIG. 11 is a rear elevational view of FIG. 8; and,
 FIG. 12 is a side elevational view of FIG. 8.
